(57) **CLAIM**

The ornamental design for a dusting implement, as shown and described.

DESCRIPTION

FIG. 1 is a top plan view of my new design for a dusting implement; the bottom plan view is a mirror image of the top plan view;

FIG. 2 is a front elevational view of the dusting implement; FIG. 3 is a rear elevational view of the dusting implement; and,

FIG. 4 is a front perspective view of the dusting implement. The broken lines shown in the dusting implement in FIGS. 1 and 4 represent stitching.
